UNITED STATES PATENT OFFICE.

ALFRED WILKINSON, OF BRADFORD, ENGLAND.

WARP STOP-MOTION FOR LOOMS.

SPECIFICATION forming part of Letters Patent No. 628,731, dated July 11, 1899.

Application filed March 15, 1897. Serial No. 627,711. (No model.)

To all whom it may concern:

Be it known that I, ALFRED WILKINSON, a subject of the Queen of England, residing at Bradford, England, have invented certain new and useful Improvements in Warp Stop-Motions for Looms, (for which I have obtained Letters Patent in England, dated January 17, 1896, No. 1,206; in Belgium, dated February 22, 1897, No. 126,543, and in France, dated December 18, 1896, No. 262,314,) of which the following is a specification.

This invention relates to improvements in looms for weaving; and its object is to provide a simple and efficient stop-motion or mechanism for automatically stopping the loom when one or more of the warp-threads break.

To fully describe my invention, reference is made to the accompanying drawings, forming a part of this specification, in which similar letters of reference indicate corresponding parts in each of the figures.

Figure 1 represents an end elevation of such parts of a loom as are necessary to illustrate my invention. Fig. 2 represents a plan view, and Fig. 3 a back view, of the same. Figs. 4 to 9 represent separate detail views, on a larger scale, hereinafter referred to.

The side frames A and A², the tappet-shaft A³, the crank-shaft A⁴, the warp-beam A⁵, the back beam A⁶, and the starting-lever A⁷ are of any ordinary construction. The warp (shown by the broken lines W in Figs. 1, 6, 7, and 8) passes in the usual manner from the warp-beam A⁵ over the "back beam" A⁶ and into the loom. A light roller B, covered with "card-filletting" or wire card-clothing or a suitable equivalent, is mounted over the warp, so as just to clear it. This roller is supported at one end by the journal-spindle B² in a bearing formed in the bracket C, (fixed to the side frame A,) through which the journal-spindle projects, and the other end by the journal-spindle B³, which fits into a bearing formed in the center of the end of the shaft D, which shaft D is mounted in bearings formed in the bracket C², fixed to the side frame A². The shaft D is driven by the toothed wheel D², fixed upon its outer end, engaging the pinion D⁴, mounted upon the stud D⁵ and fixed to the sprocket-wheel D⁶, driven by a chain (not

shown) from the sprocket-wheel D⁷ upon the crank-shaft.

A brush E, having a row of bristles e along each side, is mounted in bearings formed in the brackets C C² parallel to the roller B and in such a position that during its periods of rest the ends of the bristles e along the side adjacent to the roller B touch the "dents" or wire of such roller, as shown in Fig. 1. The brush E is intermittently turned half a revolution during each rotation of the roller B by means of the segmental wheel D² on the shaft D engaging the wheel E², connected to the brush E. These wheels are shown on a larger scale in Figs. 5 and 9. Flats E³ E³ are formed diametrically opposite each other upon the boss of the wheel E², and the arm E⁵, pivoted upon the stud E⁶, bears upon the uppermost flat, as shown in Fig. 5, and holds the "brush" stationary after each movement. The tension of the spiral spring S, stretched between the end of the arm E⁵ and the fixed hook E⁷, determines the pressure of the arm E⁵ upon the flats E³. The roller B is driven in the direction of the arrow shown in Fig. 1. Therefore the brush E is rotated in the opposite direction, and it is located in such a position in relation to the warp that at each movement the bristles pass between the warp-threads and brush them in the opposite direction to that in which the warp is moving. Consequently in case a warp-thread is broken the broken end is brushed back until engaged by the dents of the roller B.

The roller B is very lightly driven by the antifriction-roller B⁴, mounted between lugs B⁵ on its end, resting against the bottom of one of the two snails or inclines B⁶, formed on the face of D², as shown on a larger scale in Fig. 9. A spring F, fixed to the bracket C, bears against the end of the journal-spindle B² and normally keeps the antifriction-roller B⁴ against the bottom of one of the snails B⁶, and the inclination or angle of the snails is such that they normally drive the roller B; but in case it is retarded in any way—as, for instance, by it having laid hold of a broken end of warp—the roller is free to stop, and the further movement of the snail moves the roller longitudinally in the direction of the arrow, Fig. 3. Ratchet-teeth B⁸ are

formed on the outer end of the roller B, which teeth engage the pawl H and positively hold the roller from revolving immediately its longitudinal movement takes place, and the 5 further longitudinal movement of the roller forces the pawl outward. The pawl H is rigidly fixed on the short shaft H², mounted in a bearing formed in the bracket C, and the arm H³ is fixed upon the other end of the shaft 10 H². The arm H³ extends into the forked arm J of the bell-crank lever J², and its other arm J³ is coupled by the rod J⁴ to the starting-lever A⁷. It will thus be seen that before the 15 longitudinal movement is completed the starting-lever A⁷ is disengaged from the usual notch A⁸, Fig. 2, in the catch-plate A⁹ of the loom, and it consequently springs inward and stops the loom in the same way as when stopped by the ordinary weft-fork motion. 20 To clear the pawl H from the teeth B⁸ and leave the roller B free to be returned to its normal position, the side J⁵ of the slot J⁶ in the catch-plate is horizontally inclined. This has the effect of forcing the lever forward as 25 it springs inward, and thus drawing the rod J⁴ in the direction of its previous movement and lifting the pawl clear of the teeth B⁸. When the lever A⁷ is moved back to the position shown, to restart the loom the whole of the 30 parts are thereby replaced in the position shown in Figs. 1, 2, and 3, and to make the spring F rigid enough to at once force the roller B longitudinally back to its normal position the drop-piece L is provided. This drop- 35 piece is pivoted upon the stud L², fixed on the approximately vertical branch H⁴ of the arm H⁸. The drop-piece L is so arranged that as soon as the pawl H is forced back, so as to move the shaft H² and branch arm H⁴, it drops 40 down behind the spring F to the position shown in Fig. 4, and thus solidly backs up the spring; but as soon as the roller B is pushed back far enough to clear the teeth B⁸ off the pawl projection L³ comes in contact with the 45 end of the stud L⁴, fixed in the bracket C, and the slight further movement of the arm H⁴ causes the stud L⁴ to lift the drop-piece to the position shown in Fig. 3. This leaves the spring F quite free and the only resistance 50 opposed to the longitudinal movement of the roller B when the next warp-thread breaks and the loom requires to be stopped. A projection L⁶, playing between the steady-pins L⁷ L⁷, is provided on L to limit its movement. 55 The pin F², fixed in the arm H⁴, is provided for the end of the spring F to bear upon and confines its movement in relation to the arm H⁴ in that direction. A weighted arm H⁵ is 60 preferably fixed to the short shaft H² and tends to keep the pawl H in its normal position until engaged by the teeth B⁸. A set-screw H⁶ is fixed in a projection H⁷ on the under side of the pawl H, by which the normal position of the pawl may be adjusted. 65 I also employ a vibrating brush N beneath the warp to assist the brush E. This brush is mounted upon arms N², loosely pivoted to

the quadrants N³ N³ in such a manner that the said arms are free to move in relation to the quadrants within the limit allowed by the 70 projections N⁴ and N⁵ upon the quadrants. The quadrants N³ are fixed on the rocking shaft N⁶, which is operated by the eccentric N⁷ on the tappet-shaft connected to the arm N⁸ on N⁶ by the connecting-rod N⁹. The 75 brush N brushes the warp in its backward movement, and it is withdrawn from contact with the warp during its reverse movement. This is effected in the following way: In its backward movement the brush passes from 80 the position shown in Fig. 6 to that shown in Fig. 7, and it brushes the warp during the latter part of this movement. Then on the reverse movement the quadrants N³ commence to move without practically moving 85 the brush, excepting to withdraw it from the warp, and when that has taken place the projections N⁵ upon the quadrants engage the arms N², as shown in Fig. 8, and carry the brush forward until it falls over the arms N² 90 against the projections N⁴ to the position shown in Fig. 6.

A portion of the bristles of the brush E are preferably inclined, as shown in Fig. 2, to more readily lay hold of the ends. 95

Both the bearings for the brush E and the roller B are of such a construction that the brush and roller may be readily removed and replaced.

I claim—

1. In a weaving-loom the combination with the roller B, capable of being moved longitudinally and means for rotating it, of the rotatable brush E, mechanism for rotating said brush intermittently, a starting-lever, a catch-plate therefor, and connections intermediate the roller B and said starting-lever whereby the continued longitudinal movement of the roller effects the release of the starting-lever from the catch-plate to stop the loom. 100

2. In a weaving-loom, the combination with the roller B, capable of being moved longitudinally, means for rotating said roller, of teeth formed on the end of said roller, a pawl adapted to be engaged with the teeth, a rock-arm with which the pawl is connected, a starting-lever, and connections between the latter and the rock-arm whereby said starting-lever is actuated as described when the rock-arm is rocked, for the purpose specified. 115

3. In a weaving-loom, the combination with the roller B, capable of being moved longitudinally, means for rotating said roller, of teeth on the end of said roller, a pawl adapted to be engaged with the teeth, a rock-arm with which the pawl is connected, a starting-lever, connections between the latter and the rock-arm, whereby said starting-lever is actuated as described when the rock-arm is rocked, a spring adapted to force the roller back to 125 normal position when the pawl is free from the teeth of the roller, a piece L pivotally connected with the rock-arm and adapted to co-operate with the spring as described, said 130

piece having a projection adapted to come in contact with a fixed part or abutment to effect the lifting of the piece, for the purpose specified.

5 4. In a weaving-loom, the combination with the roller B, and rotary brush E and means for rotating said roller and brush, of the vibrating brush N arranged to brush the warp, a rock-shaft, quadrants thereon, means for 10 rocking the said rock-shaft, arms loosely pivoted to the quadrants and supporting the brush N, and stops on the quadrants for limiting the throw of the said pivoted arms.

5 5. In a loom the combination of a warp stop-15 roller movable longitudinally, a driven gear having frictional contact with said roller to drive the same, a cam between said gear and roller for moving the latter longitudinally when its rotary motion is impeded, and means 20 for engaging and holding said roller when moved longitudinally out of its normal position, and a brush adapted to be rotated intermittently in a direction opposite to that of the warp stop-roller, said brush operating to 25 brush back the end of a broken thread until engaged by the roller.

6. In a loom the combination of a warp stop-roller movable longitudinally and having at one end a ratchet, a pawl for engaging said 30 ratchet when the roller is moved longitudinally, a driven gear having thereon an annular cam operating against a projection on the roller to drive the latter and to move it longitudinally into engagement with said 35 pawl when its rotary motion is impeded, a brush adapted to be rotated intermittently in a direction opposite to that of the warp stop-

roller and to brush back the end of a broken thread until engaged by the roller, teeth on the end of the roller, a pawl adapted to be 40 engaged by the teeth, a rock-arm connected with the pawl, a starting-lever, and connections between the latter and the rock-arm whereby the starting-lever is actuated as described when the rock-arm is rocked. 45

7. In a weaving-loom, the combination with the roller B capable of being moved longitudinally and means for rotating it, of the rotatable brush E, mechanism for rotating said brush intermittently comprising a rotatable 50 shaft, a segmental toothed wheel mounted thereon, a toothed wheel carried by the brush and having its hub provided with oppositely-located flat bearing-surfaces, said wheel gearing with the said segmental wheel, a 55 spring-actuated pivoted arm adapted to bear upon the said flat bearing-surfaces, ratchet-teeth on one end of the roller, a pawl adapted to be engaged and operated by the teeth when the roller is shifted longitudinally, a 60 shaft for said pawl, an arm on said shaft, a bell-crank lever one of whose arms is engaged by the first-named arm, a starting-lever and connections between the latter and the other arm of the bell-crank lever, all arranged for coöperation as and for the purpose specified. 65

In testimony whereof I have hereunto set my hand in the presence of the two subscribing witnesses.

ALFRED WILKINSON.
